(57) **CLAIM**

The ornamental design for a swim fin having extending tips, as shown and described.

DESCRIPTION

FIG. 1. Is a perspective view of my swim fin having extending tips with the dotted showing being for illustrative purposes only;

FIG. 2. Is a right side view thereof with the left side view being a mirror image thereof;

FIG. 3. Is a front view thereof;

FIG. 4. Is a rear view thereof;

FIG. 5. Is a top view thereof;

FIG. 6. Is a bottom view thereof;

FIG. 7. Is a top perspective view of a second embodiment of my swim fin as shown in FIG. 1;

FIG. 8. Is a right side elevational view of the embodiment shown in FIG. 7 with the left side elevational view being a mirror image thereof;

FIG. 9. Is a front view of the FIG. 7 embodiment;

FIG. 10. Is a rear view of the FIG. 7 embodiment;

FIG. 11. Is a top view of the FIG. 7 embodiment; and,

FIG. 12. Is a bottom view of the FIG. 7 embodiment.
